UNITED STATES PATENT OFFICE.

DANA K. ALDEN, OF STERLING, MASSACHUSETTS.

STOVE OR OVEN DOOR.

SPECIFICATION forming part of Letters Patent No. 258,208, dated May 23, 1882.

Application filed January 3, 1882. (No model.)

To all whom it may concern:

Be it known that I, DANA K. ALDEN, of Sterling, in the county of Worcester and State of Massachusetts, have invented a new and useful Improvement in Stove or Oven Doors; and I do hereby declare the same to be described in the following specification and represented in the accompanying drawings, of which—

Figure 1 is a front elevation, and Fig. 2 a transverse section, of an oven or stove door having my improvement, which relates to such a door when having fixed in it a plate or panel of glass.

The great difficulty experienced in the use of such doors is the cracking of the glass when subjected to the heat of the stove or oven.

In carrying out my invention the pane or panel of glass is to have a round hole or holes made through it at its center, or thereabout. I have found in practice that when the plate has such a hole in it there is little, if any, danger of the plate becoming cracked by the heat. Upon such a plate heated to a high degree I have thrown cold water without it becoming cracked by sudden reduction of temperature. A like rise to a high degree of heat will not cause the plate to be cracked. In connection with the hole I use a covering-plate held in place by a screw-bolt and nut, the bolt having to its shank a diameter less than that of the hole, and going through the said covering-plate and hole, and screw into the nut, which

should extend across or cover the hole, the object being to prevent air from going through the hole. In some cases, however, I so apply 35 the covering-plate and screw and nut as to enable the plate to be turned aside, so as to uncover the hole more or less to allow air to pass through it.

In the drawings, A denotes the oven or stove 40 door, generally made of cast-iron, B being the glass panel or plate fixed in and supported by such door. The hole in such plate is shown at a, the covering-plate at b, the confining-bolt at c, and the nut at d, all being arranged as 45 represented.

I claim as my invention as follows, viz:

1. The combination, with a stove or oven door, of a plate or panel of glass fixed therein and provided with a hole extending through 50 it, (the said plate,) as and for the purpose as set forth.

2. The combination of an oven or stove door with a plate or panel of glass, perforated as described, and fixed therein, and with a covering-plate and screw-bolt and nut, arranged, substantially as set forth, with the perforation or hole of the said glass panel or plate, all being essentially and for the purpose as specified.

DANA K. ALDEN.
